UNITED STATES PATENT OFFICE.

LOUIS GUSTAVE BRÉGUET AND PAUL ALBERT BRÉGUET, OF GENEVA, SWITZERLAND.

WIRE-DRAWING BENCH.

Application filed January 12, 1924, Serial No. 685,807, and in France August 18, 1923.

The present invention relates to wire-drawing machines, and it resides in the provision of certain improved features of construction and arrangement of parts whereby machines of the character indicated can be run at much higher speeds than has heretofore been possible; such speeds reaching as high as 100 kilometers per hour.

An embodiment of the invention is illustrated in the accompanying drawing, wherein:

Figure 1 is a front view of the improved machine;

Fig. 2 is a side elevation thereof;

Fig. 3 is an enlarged view of one of the cooling vessels and its associated drawing plate.

As shown in said drawing the improved machine embodies two vertical walls or sides ²⁰ *a'* and *b*, supported upon a bed plate *a*, and wherein are journaled two pairs of diverging shafts *c⁴*, *c⁵* *c⁶* and *c⁷*, respectively carrying the stepped drawing cones *c*, *c'*, *c²* and *c³*. These cones are disposed outside of wall *b* (to the right of the wall in Fig. 2), and between said wall and the wall *a'* the drawing shafts are designed to carry the driving pulleys whereby they are rotated, illustration of said pulleys being omitted as forming ²⁵ no part of the actual invention.

A pair of V-shaped cooling vessels *e* and *e'*, one substantially between the cones *c*, *c'*, and the other between the cones *c²*, *c³*, is provided, the rear wall of each vessel being ³⁰ constituted by a drawing plate *f*, *f'*; said plates being disposed perpendicularly to the strands of wire undergoing treatment. The vessels are each divided by vertical partition plates into a series of compartments, the ³⁵ number of which corresponds to the number of drawing dies or the like with which the plates *f* and *f'* are equipped, so that there will be one compartment for each thickness of wire; and the plates of each vessel are ⁴⁰ preferably stepped so as to cause the cooling liquid to overflow from one compartment to the next. The compartments of larger sizes are reserved for the thicker strands or sections of wire and the smaller sized compartments are reserved for the thinner strands or sections.

The wire runs from an outside supply over a roller *g* to the first step of the lower cone *c'*; thence through the first die in plate ⁴⁵ *f* and through vessel *e* to the first step of the upper cone *c*; then back to the second

step of cone *c'*; then through the second die in plate *f*, and again through vessel *e* to the second step of cone *c*, and so on, until it has passed around all the steps of the two cones ⁵⁰ *c* and through all the dies in plate *f*. It is then subjected to the action of the second pair of cones *c²*, *c³* and the cooling vessel *e'* and its associated die plate or wall *f'*, being led from the last step of cone *c* to the first ⁵⁵ step of cone *c²* and then through plate *f'* and vessel *e'* to the first step of cone *c²*. This is repeated until, as before, it has passed around all the steps of the two cones and through all the dies in plate *f'*, whereupon ⁶⁰ it is led around a pair of guide rollers *m* and *k* to a roller *i* around which it passes and from which it is led to a winding drum *h*. The roller *i* is subjected to frictional engagement by a flat spring *n* attached to a bracket ⁶⁵ *o*, the purpose being to obtain an even winding of the wire on drum *h*.

In Fig. 2, *r* indicates the main drive shaft of the machine carrying the fast and loose pulleys *s* and *s'* with which a belt shifter *t* ⁷⁰ is associated. This device is moved in one direction by means of a treadle *p* connected with it through a suitable lever system *v*, and in the other direction by means of a spring *w*.

The improved arrangement possesses the advantage of affording a good general survey of all the dies and wires; and the oblique position of the drawing plates, which is required by the oblique position of the wires, ⁷⁵ is more convenient in case of a wire rupture than a horizontal arrangement. Furthermore, while the flow of the liquid from one compartment to the next assists the cooling action, the passage of the wire upward ⁸⁰ through the vessels causes it to carry some of the liquid along with it, so that the liquid remains in contact with the wire for a longer period than that consumed by the actual disposition of the wire in the vessels. The ⁸⁵ principal advantage, however, is the fact that the speed of travel of the wire can be greatly increased without danger of the wire breaking.

We claim as our invention:

A wire drawing bench, comprising a pair of rotary drawing elements around which the wire passes a plurality of times, one element being disposed above and to one side of the other to cause the wire to travel in a ⁹⁰ direction oblique to the horizontal; a V-shaped vessel to contain a cooling liquid dis-

posed directly between the drawing elements in the path of travel of the wire; a single die-equipped drawing plate for said vessel and constituting the wall thereof that faces
5 the lower drawing element, said plate being disposed obliquely to the horizontal and perpendicularly to the wire; and a plurality of internal partitions in said vessel dividing its interior into a series of compartments of
10 different sizes equal in number to the number of dies in the drawing plate and through

which the wire passes from said dies; said partitions being disposed in stepped relation so as to cause the liquid to overflow from one compartment to the next, the compartments of larger sizes being reserved for the thicker strands of wire, and those of smaller sizes for the thinner strands. 15

In testimony whereof we affix our signatures.

LOUIS GUSTAVE BRÉGUET.
PAUL ALBERT BRÉGUET.
